OF DELAWARE

ELECTRIC CONTROL SYSTEM FOR OIL BURNERS

Application filed June 7, 1929. Serial No. 369,061.

This invention is directed to an improvement in oil burner controlling mechanism or an electric control system for oil burners and provides a controlling mechanism which 5 we believe embodies novel control features in the operation of oil burners by way of the control for the ignition, the venting of the fuel feed tank and opening of the line under abnormal conditions, etc., all of which 10 will appear hereinafter.

The drawing accompanying the application is diagrammatic.

Referring to the drawing in detail, 1 designates a room thermostat, 2 a boiler control 15 thermostat, 3 a mercury line switch, and 4 an ignition transformer. 5 designates blower operated mechanism for control of the line switch 3. 6 is a combustion-controlled thermostatic switch.

20 With the parts in the position shown in the diagram, we will assume that the burner is not in operation. Consequently, the blade 7 of the combustion-controlled switch 6 is on the contact 8. We will assume also that the 25 room thermostat is calling for heat, and hence the blade 9 thereof is on the contact 10 and the blade 11 of the boiler control switch 2 is on the contact 12.

With the switches in these positions and 30 under these conditions a circuit may be traced from one side of the line, by way of conductors 13 and 14 to the blade 7 of the switch 6, contact 8 of said switch, conductors 15 and 16, blade 11 and contact 12 of boiler control 35 switch 2, conductor 17, blade 9 and contact 10 of room thermostat 1, conductors 18 and 19 to mercury switch 20, through this switch, conductor 21, coil 22 of a double wound switch-controlling solenoid 23, conductors 24, 40 25, 51, contact 73 of line switch 3, conductors 52 and 26 to the other side of the line.

Energization of the coil 22 of solenoid 23 45 will effect movement of the core 27 thereof to the left, as viewed in the drawing, into contact with a pivoted arm 28 carrying an ignition controlling mercury switch 29, tipping this switch upwardly to closed position, so that a circuit will be closed to the primary 30 of the ignition transformer 4 50 and a starting circuit to winding 31 of a

double-switch and vent valve controlling solenoid 32.

The circuit to the transformer primary may be traced by way of conductors 13 and 33, mercury switch 29, which is now closed, conductor 34, primary 30, conductors 35, 25, 51, contact 73, conductors 52 and 26, to the other side of the line.

The starting circuit for the winding 31 of the solenoid 32 may be traced by way of 55 conductors 13, 33, mercury switch 29, conductors 36, 37, winding 31, conductors 38, 38', 51, contact 73, conductors 52 and 26, to the other side of the line.

The exciting of the winding 31 causes the 60 solenoid 32 to move its core 39 upwardly, as viewed on the diagram, and through the connection shown at 40 simultaneously to rock the mercury switches 20 and 41 upwardly 65 from the position shown on the diagram.

This movement of the switches 20 and 41 70 opens the circuit of the coil 22 of solenoid 23 at the contacts 42 in the right-hand end of mercury switch 20 and establishes through the switch 41 a holding circuit for the winding 31 of solenoid 32.

This holding circuit may be traced by way 75 of conductors 13 and 43, mercury switch 41, conductors 44 and 16, boiler control switch 2, conductor 17, room thermostat 1, conductors 18 and 18', mercury switch 20, conductors 45 and 37, winding 32, conductors 38, 38', 51, contact 73, conductors 52 and 26, to the other side of the line.

The energizing of the winding 31 of solenoid 32 closes a bleeder or vent valve 46 which 80 is connected through pipe 46' to a pressure feed fuel tank, 46''.

Inasmuch as the coil 22 of solenoid 23 has 85 been energized, and the core 27 thereof moved to the left to tip the switch 29, and inasmuch as the mercury switch 41 has been tipped by energization of the winding of solenoid 32 a circuit has been completed through the motor 48, by way of conductors 13 and 43, contacts 90 49 of mercury switch 41, conductor 50, through the motor, conductors 48', 38', 51, mercury line switch 3, conductors 52 and 26, to the other side of the line.

The closure of the circuit of the motor 48 95 100

will, of course, start the fan or blower 47 in operation to supply pressure to the feed tank 46" and air to the burner cup C.

Referring to the blower operated mechanism 5 for the control of the line switch 3, this mechanism comprises a cylinder 53 connected by pipe 54 to the housing of blower 47, and a float cylinder 55 communicating with the cylinder 53 through conduit 56. The conduit 56 is controlled by a flap valve 57, opening toward cylinder 53, this valve being provided with a port 58. The flow of liquid from 53 to 55 is necessarily slow, the liquid all passing through port 58, the flow in the opposite direction, however, being rapid, as in this direction of flow the valve is unseated.

The cylinder 55 is provided with a float 59, having a stem 60, this stem being provided with a member 61 adapted to cooperate with the right hand end of the core 27 of solenoid 23. The stem 60 is also provided with an operating member 62 adapted to travel between two legs 63 and 64 of a switch controlling lever 65, pivoted at 66, and adapted to control the line switch 3.

To the upper end of the stem 60 is attached a bleeder or vent valve 67 for the float chamber or pressure feed fuel tank 46", this valve, as will be understood, being additional to the bleeder or vent valve 46 above referred to and connected to the tank by pipe 67'.

With the parts in the positions assumed and the circuits traced established the burner is ready for operation and the starting up of the blower 47 will drive the liquid 68 out of the cylinder 53 through the port 58 in the flap valve 47 into the cylinder 55 to cause the float 59 in this last cylinder to rise and close the vent valve 67 on the fuel feed tank. Inasmuch as the circuit of the motor 48 is closed prior to the closing of the vent valve 67, it is apparent that the burner will receive air prior to receiving a fuel supply, and consequently the burner cup C, if an air driven type is used, will have an opportunity to be brought up to speed before receiving oil. This is a desirable operation. The vent valves 46 and 67 being closed, as above described, pressure will be built up in the fuel feed tank and oil supplied to the burner cup C through pipe P and the circuit to the primary winding 30 of the ignition transformer 4 being closed, as above noted, the oil will be ignited. When combustion is initiated it will be apparent that the blade 7 of switch 6, which as above pointed out is controlled by combustion conditions will be moved off of the contact 8 and into engagement with a fixed contact 69, to close a circuit to a second winding 70 for the solenoid 23 which is opposed to the winding 22, the circuit of which has been broken, of this solenoid. The circuit for this winding 70 may be traced by way of conductors 13, 14, switch blade 7, contact 69, conductor 71, winding 70, conductors

24, 25, 51, contact 73, conductors 52 and 26, to the other side of the line.

The core 27 of the solenoid 23, therefore, will move to the right, as viewed in the diagram, until the right hand end thereof will be interposed in the path of the member 61 being carried upwardly by the float stem 60, thereby to arrest the upward movement of this stem prior to the engaging of the member 62 on the stem with the upper arm 64 on switch controlling lever 65. The movement of the core 27 under the action of the winding 70 will permit the ignition control mercury switch 29 to open by gravity and hence open the circuit of the primary 30 of the ignition transformer and the starting circuit of winding 31 of solenoid 32. A holding circuit, previously traced, has already been established for the winding 31, so that the core of solenoid 32 remains in position.

Consequently we have a condition now where the burner is in operation, the circuit of the ignition transformer open and the core of the solenoid 23 in the path of the member 61 preventing further upward movement thereof.

When the temperature of the room being heated has risen to the desired degree, the blade 9 of the room thermostat 1 will move off the fixed contact 10 and open the holding circuit for the winding 31 of the solenoid 32, permitting the latter to drop its core, opening vent valve 46 and permitting the two switches 20 and 41 to rock to the right so that they will assume their original position shown on the drawing, which will effect an opening of the circuit of the motor 48, the blower 47 will come to rest and the burner cease operation.

Under these conditions the liquid 68 in the cylinder 55 will flow back toward the cylinder 53 until the same level is reached in both cylinders, interruption of the operation of blower 47 interrupting the supplying of pressure to the liquid 68.

The two bleeder valves or vent valves 46 and 67 are now opened again, the former due to deenergization of solenoid 32 and the latter due to descent of float 59, so that the flow of oil to the burner is interrupted, the pressure on the fuel in this tank being relieved by the opening of the two vent valves.

When the room being heated cools off sufficiently so that the room thermostat again calls for heat the operation above described will be repeated.

If for any reason ignition should not be initiated on starting up, the present invention provides for opening one leg of the supply. Assuming that the fuel did not ignite, it will be obvious that the blade 7 of the combustion controlled switch 6 will remain on the fixed contact 8 and hence the circuit of the winding 70 of the solenoid 23 will remain open and the core 27 of this solenoid will remain in its left hand position, that is in en-

gagement with the lever 28 of switch 29, as will be understood. Consequently the operation of the blower 47 will continue to force the liquid 68 out of the cylinder 53 and into the cylinder 55 to move the float 59 upwardly until the operating member 62 on the float stem hits the upper arm 64 of the lever 65, rocking the latter to the left about its pivot 66 until it entirely disengages the lever 72 which carries the line switch 3, and the latter will rock open by gravity to open the motor circuit at the contacts 73 of this switch. This of course will open one leg of the supply. In this connection it should be noted that to resume operation it is necessary that the line control switch 3 be reset by hand.

It will be understood that in normal operation when the burner ceases operation due to the room temperature having reached the degree desired the motor circuit is opened at the room thermostat 1 before the switch blade 7 has moved off the contact 69 so that the core 27 of the solenoid 23 remains in its right hand position, otherwise this core would be pulled to the left and instead of the circuit of the motor 48 being opened, as is desired, it would be opened by the rising of the float 59 which will necessitate a manual resetting of the switch 3 each time.

In the event of power failure the motor 48 of course will stop and likewise the blower 47 and if the power is off the line for a sufficient length of time the level of the liquid 68 in the cylinders 55 and 53 will assume a level permitting the float 59 to lower, thereby opening the vent valve 67 in the feed tank. The winding of the solenoid 32 on power failure is also deenergized so that the vent valve 46 will likewise open. Consequently the supplying of oil to the burner will cease and when the power comes on the line again, assuming of course that the room thermostat 1 is still calling for heat, normal operation will be automatically resumed.

In the event of a leak in the float 59, the same will sink, causing the member 62 to strike lever arm 63, pivoting the upper end of lever 65 to the right from beneath the member 72. The latter will drop by gravity and open the line at the contacts 73.

What we claim is:

1. In an oil burner mechanism having an electric motor, a blower operated thereby, a fuel tank in communication with said blower to place the fuel therein under air pressure, a vent valve for the tank and a line switch for the motor circuit, means for operating the said line switch and vent valve comprising liquid containing means, a connection therefrom to the blower whereby air pressure will cause the liquid level to rise, a float controlled by said liquid level, means operated by said float to close said vent valve and subsequently after a predetermined time to open said line switch on rise in liquid level and means re-

sponsive to combustion conditions to prevent opening of said line switch.

2. In a control system for an oil burner mechanism having a source of fluid pressure, a fuel tank in communication therewith to place the fuel therein under fluid pressure, and an electrically operated igniter, said control system comprising a vent valve for said tank, a solenoid operative when energized for actuating said valve to close, a switch in circuit with said igniter and solenoid and a second solenoid for actuating said switch.

3. In oil burner mechanism the combination of a burner motor, switching means controlling the circuit of said motor, a solenoid for actuating said switching means, an electrically operated igniter, a switch device operative when closed to energize said igniter and said solenoid, said switching means being operative when actuated by said solenoid to close a holding circuit for said solenoid, a second solenoid having two windings, the first of said windings actuating said switch device to closed position, said switching means being operative when actuated to break the circuit of said first winding, the second of said windings operating when energized to release said switch device for opening movement, and a combustion controlled switch operative on initiation of combustion to energize said second winding.

4. A control system for an oil burner mechanism having a blower, an electric motor to drive said blower, a fuel tank communicating with said blower to place the fuel therein under pressure, said control system comprising a line switch operative when open to de-energize all electrical elements, a vent valve for the fuel tank, means operated by blower pressure to first close said vent valve and a time period thereafter to open said line switch, and combustion responsive means operative on initiation of combustion within said time period to prevent said blower operated means opening said line switch.

This specification signed this 5th day of June, 1929.
